LOCK HANDLE UNIT

John R. Gerlach, Los Angeles, Calif., assignor, by mesne assignments, to The American Hardware Corporation, New Britain, Conn., a corporation of Connecticut

Application June 13, 1958, Serial No. 51,351

Term of patent 14 years

(Cl. D10—8)

Fig. 1 is a front elevational view of a lock handle unit showing my new design;

Fig. 2 is a side elevational view; and

Fig. 3 is a perspective view.

I claim:

The ornamental design for a lock handle unit, as shown.
